J. L. Mott,
Stoves,
Patented May 30, 1832.

May 30, 1852

Jordan L. Mott, New York City

Letter Patent

The Schedule referred to in these Letters Patent and making part of the same containing a description in the words of the said Jordan L. Mott himself of his improvement in Stoves for Burning Anthracite Coal.

To all to whom these presents shall come. Whereas it is known that the said Jordan L. Mott of the County and State of New York have invented constructed and applied to one a new and useful improvement in Stoves for burning Anthracite Coal. Said improvement is not confined to any particular form or combination of Stoves but is applicable to any of the Coal Stoves now in use. It consists in dividing the interior of that part of the Stove intended for fuel into two compartments by means of a partition so as to form on one side a recess to contain a supply of coal. in the other side the fire and draught and a plain or curved plate inclined with an opening between the lower edge of the partition & the plate to admit the coal to slide forward from the recess on to the grates placed at the bottom of the fire or front division as follows. Near the bottom of the Stove on the side intended for the fire place a plain or curved grate inclined from the front of the Stove upwards leaving sufficient room under it for draught and to have a fire or draw to receive the ashes. The grate to extend from the side of the Stove to nearly under a line with the lower edge of the partition. At the bottom of the recess or coal division place the curved or plain plate inclined with the lower edge against or above the edge of the grate. Its upper edge against the side of the Stove. The partition to commence at the top of the Stove or sufficiently near the top to give depth in the recess for a supply of coal and run down towards the lower edge of the curved or plain plate leaving a space between the lower edge of the partition and the curved or plain plate of say six inches (one or less) or in proportion to the depth of coal required to be burnt on the grates. If the coal be in small lumps make the distance less and increase the distance according to the size of the coal. The partition may be made double by placing other

slates, a pair, inclined or nearly so to each other to give more than twice the edge with a passage through the sides of the Stove to admit a circulation of air between the plates. The plain or curved plate and grate to be inclined sufficiently to admit the coal to slide freely from the reservoir under the lower edge of the grate to the front of the Stove. The curved and plain plate & grate may be in one piece or otherwise. The partition may have a flat or curved surface. The partition and the plain or curved plate may be made of fire brick, Soap Stone, metal or any suitable material. The door may be equal by hinged or otherwise. The reservoir may be a little larger at the bottom than the top to admit the coal to settle more freely. On the top or on the side near the top of the reservoir have an open hole of suitable dimensions for filling it with coal with a door or lid to prevent the air passing through the reservoir. On the side of the Stove iron the grate near the surface of the iron coal place a door for the removal of burning fuel. On the top or on the side near to the top of the fire division place the pipe flue or hole. If the partition or iron division is not carried to the top of the Stove the draught may be carried over the top of the reservoir from the fire division by placing the pipe flue or hole on the back of the Stove over the top of the reservoir. Have a door or opening under the curved or plain plate to admit the ashes being freed.

• **Manner of use.** - Kindles a fire on the grate, when the coal gets burning fill the reservoir with coal, and as the coal on the grate is consumed and the air expanded, that in the reservoir by means of its porosity and the inclined plane or curved plate and grate is brought forward on the grate and to the front of the door thereby keeping up a regular supply.

That which I claim as my invention and improvement is the dividing of the Stove, the inclined plates or curved plate and the inclined grate as also specified for the above mentioned purposes. In witness whereof I have hereunto subscribed my name this twenty-third day of April 1832
